UNITED STATES PATENT OFFICE.

JEROME J. AULL, OF CINCINNATI, OHIO, ASSIGNOR TO THE LUNKENHEIMER COMPANY, OF CINCINNATI, OHIO, A CORPORATION OF OHIO.

LUBRICATOR.

Application filed January 25, 1923. Serial No. 614,909.

To all whom it may concern:

Be it known that I, JEROME J. AULL, a citizen of the United States, and a resident of Cincinnati, in the county of Hamilton and State of Ohio, have invented certain new and useful Improvements in Lubricators, of which the following is a full, clear, and exact description, reference being had to the accompanying drawings, forming part of this specification.

My invention relates to sight feed lubricators for internal combustion engines in which the lubricant is contained in a reservoir usually comprising a glass cylinder with metal base and top cover and the oil is delivered by gravity through a sight feed chamber below, with the delivery controlled by a valve in the base with the valve stem extending upwardly through a central valve tube in the reservoir and projecting above the top cover. The filling opening for such lubricators is located in the top cover at one side of the central portion and as such lubricators are generally subjected to back pressure it is necessary that this filling opening shall be properly closed.

It is the special object of my invention to provide for this class of lubricators a simple, cheap and effective closure for the filler opening, which will operate automatically to seal the opening when the usual slide or scutcheon is shifted to cover the opening.

The invention consists of that certain novel construction and arrangement to be hereinafter particularly pointed out and claimed.

In the drawings.

Figure 1 is a central vertical section of my improved lubricator.

Figure 2 is a perspective view of the upper portion thereof.

The lubricator except for the means for closing the filler opening is of the usual and familiar construction in which 1 is a glass cylinder mounted on a flanged base 2 upon which is screwed the sight feed cage comprising a casing 3 with side windows 4 covered by a small glass cylinder 5. The sight feed chamber is also provided with a baffle device 6 and below the baffle is the usual ball check valve 7.

The reservoir is covered by a flanged cover

plate 8 which fits down over the glass cylinder 1. Extending up from the central portion of the base 2 is the tube 9 which projects through a central opening in the cover, and the portion above the cover is screw-threaded to receive a nut 10 by means of which the cylinder is securely clamped between the cover and base, a washer 11 being supplied below the nut. Between the nut and washer is a disk 12 which is provided with a spring arm 13 extending upwardly to engage a milled cap piece 14, which is screwed upon the upper end of the tube 9. The valve stem 15 extends up through the tube and is provided at the upper end with the usual snap lever 16 which bears upon the upper face of the cap piece 14 and serves to raise or lower the valve 17 under the tension of the coiled spring 18 on the valve stem. An equalizing pipe 19 connects an opening 19 through the base into the sight feed chamber with the upper end of the reservoir. All of the construction above described is of the ordinary kind and forms no part of the present invention which, as stated, relates to the sealing of the feed opening 20 in the top cover.

Mounted loosely on the tube 9 beneath the washer 11 is a plate 21. This plate extends laterally flush with the top surface of the cover plate beyond the feed opening where the plate is enlarged and cut away to provide space for a washer 22 larger than the feed opening 20, which washer is seated in the plate opening. The outer end of the plate is curved over on itself to form a spring arm 23, which bears upon the washer to hold it tight against the cover, while still permitting the plate to be swung from side to side with the curved-over portion serving as a handle as well as a spring arm.

An effective seal for the feed opening 20 is thus obtained at very slight expense and without the necessity of providing any screwthreaded cap for the opening or designing any other sealing device which has to be manually operated. A stop 24 is provided on the cover against which the arm is shifted to close the feed opening, with the spring arm 23 holding the washer 22 and the washer carried by the plate 21. There is also no liability of the scutcheon plate be-

coming loose and accidentally opening while in use.

Having thus described my invention, what I claim as new and desire to secure by Letters Patent, is:—

In combination with a lubricator having a lubricant reservoir and an opening for supplying lubricant to the reservoir, a plate rotatably mounted on the lubricator, said plate

having an aperture adapted to register with said opening, a washer in said aperture, the outer portion of said plate bent over on itself to act as a handle and the extreme end of said bent over portion bearing against the washer to urge the latter against the wall of the lubricator to seal said filling opening.

JEROME J. AULL.
